CLAIM

The ornamental design for a dental device connection adapter, as shown and described is claimed.

DESCRIPTION

FIG. 1 is an isometric view of a dental handpiece sheath showing our new design;

FIG. 2 is a first side view thereof;

FIG. 3 is a second side view thereof;

FIG. 4 is a front view thereof;

FIG. 5 is a back view thereof;

FIG. 6 is a top view thereof; and,

FIG. 7 is a bottom view thereof.

The broken lines shown in FIG. 7 represent portions of the dental handpiece sheath that form no part of the claimed design.
